Robert Montgomery

United States Patent Office.

RICHARD MONTGOMERY, OF NEW YORK, N. Y.

Letters Patent No. 63,077, dated March 19, 1867.

IMPROVEMENT IN CURVED CORRUGATED STEEL PLATES AS AN ARTICLE OF MANUFACTURE.

The Schedule referred to in these Letters Patent and making part of the same.

TO ALL WHOM IT MAY CONCERN:

Be it known that I, RICHARD MONTGOMERY, of the city, county, and State of New York, have invented a certain new, useful, and improved article of manufacture from which to construct Furnaces, Steam Chimneys, and Flues for Steam Boilers; and I do hereby declare that the following is a clear, full, and exact description thereof, reference being had to the accompanying drawings, forming a part of this specification, in which—

Figure 1 represents a plan view of a horizontal flue made from my improved article of manufacture.

Figure 2 represents a section on line A. B, fig. 1, looking in the direction of arrow 1.

Figure 3 represents an end view of fig. 1, looking in the direction of arrow 2, fig. 1; and

Figure 4 represents an end view of part of a furnace.

In the application and use of the invention patented to me on the 29th day of October, A. D. 1850, it has been found that many of the difficulties which were before met with in the construction of steam boilers have been obviated; still, in the use of corrugated iron flues for steam-boiler furnaces and steam chimneys there have been great difficulties resulting from scales forming on the iron, and many plans have been resorted to to obviate the same; such plans, for instance, as the application of various chemical compounds to the interior of the boiler, and also galvanizing the same. All of these plans are, however, attended with much expense and inconvenience. To obviate these and other objections which have been found to exist, led me to make a series of costly experiments, which resulted in the present invention.

In the production of my improved article of manufacture, steel is subjected to such pressure as is sufficient to roll it (when properly heated) into thin sheets, after which it is pressed through corrugated and sweeping rolls, whereby it is corrugated and properly curved, as shown in the drawings. When it is to be used in the construction of tubular flues, as shown in figs. 1, 2, and 3, the edges are riveted together, as shown in figs. 2 and 3; and when used for furnaces, as shown in fig. 4, the edges may be fastened to base-pieces in any proper manner.

Some of the advantages resulting from my present invention will now be stated: First. Scales are not so liable to form, in consequence of the hard and smooth surface of the steel as compared with iron. Second. The flues are not so liable to be injured and destroyed by the action of the fire, since much thinner sheets can be used without at all affecting the strength of the flues than if they were composed of iron. Now, as thin sheets of metal transmit heat much quicker than thick ones, the interior of the flues is not liable to be exposed to overheating. Third. More steam will be generated with the same amount of fuel than in the case of iron flues of the same strength, since the heated gases are not so liable to pass through the flues without generating steam in consequence of the sensitive nature of the thin steel plates. Fourth. The weight of the material is reduced nearly one-fourth, and that, too, while the strength and durability are increased. Fifth. The material being properly curved as well as corrugated, can be manufactured and put into the market all ready for use either in the construction of new flues or the repair of old ones, thus obviating the delay which might result from a necessity of corrugating and curving the material for any particular case.

Having described my invention, what I claim as new, and desire to secure by Letters Patent as an improved article of manufacture, is—

Curved corrugated steel for the construction of steam chimneys, furnace and flues for steam boilers, and for other purposes, substantially as described.

In witness whereof I have hereunto subscribed my name.

RICHARD MONTGOMERY.
